PENNSYLVANIA.

FIREPROOF PARTITION.

1,137,165.

Specification of Letters Patent. Patented Apr. 27, 1915.

Application filed July 9, 1914. Serial No. 849,913.

To all whom it may concern:

Be it known that we, HAROLD K. PAXSON and ELMENDORF J. HEDDEN, citizens of the United States, residing, respectively, at 5 Cynwyd and Bala, county of Montgomery, and State of Pennsylvania, have invented a new and useful Improvement in Fireproof Partitions, of which the following is a full, clear, and exact description, reference being 10 had to the accompanying drawings, which form a part of this specification.

The object of our invention is to provide a partition, adapted for use in fire-proof or slow burning construction, which will be 15 staunch, durable and comparatively inexpensive.

In constructing partitions it is known to employ composition or plastic boards; but the usual construction in which such boards 20 are employed lacks the rigidity and durability which it is desirable that the partitions should have.

The object of our invention, more specifically stated, is to externally support and 25 reinforce these boards in a comparatively inexpensive manner and at the same time in such a way as to impart to the partition the desired strength and durability.

In the drawings, which show preferred 30 embodiments of our invention: Figure 1 is an elevation showing the external framework of the partition and the wires for externally supporting and reinforcing the partition. Fig. 2 is an elevation of the partition, with the supporting and reinforcing wires omitted, showing the arrangement of 35 boards. Fig. 3 is a detail elevation of a part of the partition with the spaces between adjacent boards exaggerated for purposes of clearness. Fig. 4 is a section on the line 4—4 of Fig. 3, the relative thickness of the boards 40 being exaggerated for purposes of clearness. Fig. 5 is a perspective view showing the means for fastening the wires to the sills and 45 to the boards. Fig. 6 is a cross sectional view of means for fastening the ends of the wires in concrete or stone construction.

The boards forming the partition, which are approximately square (say 36" high, 50 32" wide and one inch thick), are arranged in the manner shown in Figs. 2 and 3; that is, the boards are arranged in horizontal rows, with adjacent rows arranged in staggered relation so that the vertical joint between two boards of a row alines with the

vertical center line of the board above and below. Before the boards are erected, vertical supporting and reinforcing wires are stretched between the upper and lower horizontal stringers as shown in Fig. 1, these 60 wires being spaced apart a distance equal to one-half the width of a board and in such position that each wire will aline with the joint between two adjacent boards of one horizontal row and extend along the vertical 65 center line of a board in the next adjacent horizontal row.

In the drawings, *a*, *b*, *c*, represent the boards of the three horizontal rows respectively; *d*, *d*, the vertical stringers constituting the ends of the partition; *e*, *e*, the horizontal stringers or sills constituting the top and bottom of the partition; and *f*, *f'*, the vertical external reinforcing wires. The wires may be secured to the stringers *e*, *e*, by 75 means of staples *g*.

The wires are connected to the boards, so as to externally support and reinforce the same, in the following manner. Taking one of the wires *f*, which extends in front, and 80 along the vertical center line, of two boards *a* and *c* and alines with the joint between two of the boards *b*, and starting at the top: the wire extends over washers *h*, applied to one side (which I shall call the face) of the 85 board *a* near its upper edge, at about its center and near its lower edge. These washers may be of any suitable construction. I have found it convenient to employ washers formed of thin flat sheet metal having V- 90 shaped end recesses. Other washers are applied to the other side (which I shall call the back) of the board and immediately opposite the washers applied to the face of the board. In other words, the washers are arranged in pairs, one washer of each pair applied to the front and the other applied diametrically opposite thereto to the back.

A fastening wire *i* extends through holes *k* in the board and over the front washer *h* 100 and wire *f* and over the rear washer *h*, thereby securely retaining the wire *f* against the face of the board *a*. The wire *f* thence extends between the adjacent edges of two boards *b*, *b*, being brought to the back of the 105 partition at a point midway between the top and bottom of the joint and there extending over a washer *h* applied to the back of the boards *b*, *b*, so as to span the joint. A washer *h* is applied to the face of the board 110

immediately opposite the last named washer, and a fastening wire *i* is applied as above described. Two other pairs of washers are similarly applied to the front and back of the partition near the upper ends of this joint, the wire *f* extending over the washers on the face of the partition. The wire *f* thence extends in front, and along the vertical center line, of one of the boards *c* of the lower row and is secured thereto in the same manner as it is secured to the board *a*.

Taking one of the wires *f'*, the same extends in front of a board *b* and through the joints between two adjacent boards *a*, *a*, and two adjacent boards *c*, *c*, being secured to the back of the partition midway between the upper and lower ends of each joint.

It will be understood that in initially stringing the wires *f* they are made as taut as possible, but it is not possible to draw the wire so taut that it cannot be pulled sidewise to the limited extent required to cause the wire to extend from front to back of the partition. The zig-zag course through which each wire extends after the partition is erected involves a stretching of the wire to practically its limit so that it cannot, by sidewise pressure, be further distorted. Consequently the wire structure supporting the boards is substantially rigid, and the partition as a whole is therefore very staunch and stable even before the coats of plaster are applied thereto.

The boards are so constructed, preferably of a material such as gypsum, reinforced internally, that the final coats of plaster can be applied directly to the opposite sides of the partition and will adhere thereto as closely as they will to preparatory coats of rough plaster. After the partition has been plastered, it is as rigid and inflexible as a partition of any known construction.

The construction is comparatively inexpensive, in that the cost of material is not great and the expense of the foundation for the plaster, such as metal lath, and of initial rough coat of plaster is entirely eliminated.

In Fig. 6 is illustrated a modification applicable to concrete or stone construction. Instead of fastening each individual vertical wire *f* to the sills by means of expansion bolts, a stringer or header, shown as a channel *m*, is secured by expansion bolts *n* to the concrete and the ends of the wires are passed through holes in the angle-bar and then looped around and firmly secured. It will be understood, however, that the invention is not limited to any particular means of securing the ends of the vertical wires.

Having now fully described our invention, what we claim and desire to protect by Letters Patent is—

1. A partition comprising boards arranged in rows in which the boards of one row break joint with the boards of an adjacent

row, external supporting and reinforcing wires spanning the rows and each extending over one side of a board of one row and alining with the joint between two boards of an adjacent row, said wire extending through said joint from one side to the other of the partition, and means to fasten each wire to hold it in the position specified.

2. A partition comprising boards arranged in rows in which the boards of one row break joint with the boards of an adjacent row, external supporting and reinforcing wires spanning the rows and each extending over one side of a board of one row, thence through the joint between two boards of the next row from one side to the other of the partition, thence back through the same joint to the first named side of the partition, and thence over the side of a board in the next row, and means to fasten the wires in the relation specified.

3. A partition comprising boards arranged in rows, there being a number of boards in each row, external supporting and reinforcing wires each of which extends along the partition and alines with a joint between boards and extends through said joint from one side of the partition to the other and crosses a joint between boards extending at right angles to the first joint, and securing devices spanning each wire and arranged on opposite sides of the second joint.

4. A partition comprising boards and external supporting and reinforcing wires each of which extends along the partition and from one side thereof to the other and through joints between the boards, a series of washers each of which spans a joint and lies under a wire and engages the two boards on opposite sides of the joint, and securing wires extending through the boards and over the washers.

5. A partition comprising boards and external supporting and reinforcing wires each of which overlies one side of a board and thence extends between the joints of two adjacent boards from one side of the partition to the other, washers lying between the board and the wires where the latter overlie the sides of the boards and other washers spanning said joints and lying under the wires.

6. A partition comprising boards arranged in rows in which the boards of one row break joint with the boards of another row, external supporting and reinforcing wires spanning the rows and each extending over one side of a board of one row and alining with the joint between two boards of an adjacent row, and extending through said joint from one side of the partition to another, and a series of washers each of which spans a joint and lies under a wire and engages the two boards on opposite sides of a joint.

7. A partition comprising boards arranged in rows in which the boards of one row

break joint with the boards of an adjacent row, external supporting and reinforcing wires spanning the rows and each extending over one side of a board of one row, thence 5 through the joint between two boards of the next row from one side to the other of the partition, thence back through the same joint to the first named side of the partition, and thence over the side of a board in the 10 next row, washers between the sides of the boards and the wires extending thereover, and washers spanning the joints of the

boards and extending between the margins of adjacent boards and the wires alining with the joints. 15

In testimony of which invention, we have hereunto set our hands, at Philadelphia, on this 7th day of July, 1914.
